UNITED STATES PATENT OFFICE.

GEORGE W. MEYER AND CHARLES A. ROOS, OF CINCINNATI, OHIO.

ADJUSTABLE SHORE.

1,395,649.

Specification of Letters Patent.

Patented Nov. 1, 1921.

Application filed November 28, 1919. Serial No. 341,047.

To all whom it may concern:

Be it known that we, GEORGE W. MEYER and CHARLES A. Roos, citizens of the United States, residing at 3356 Gano avenue and 5 2832 Linwood road, Cincinnati, respectively, in the county of Hamilton and State of Ohio, have invented new and useful Improvements in Adjustable Shores, of which the following is a specification.

10 Our invention relates to what are commonly known as "shores" or extensible and adjustable supports used in "shoring" up any work requiring temporary support, as in building construction of various kinds; 15 and is intended to simplify and improve the construction, lessen the relative weight with a view to ease of manipulation and facility of use and transportation, and assure integrity of action under load; besides lessening 20 the cost of construction, use and transportation in quantities.

To this end our invention consists in the shore constructed and operative as herein-after described and illustrated in the accompanying drawing herewith submitted and forming part of this specification.

In the accompanying drawings illustrating the preferred form of our invention.

Figure 1 is a front, and Fig. 2 a partial 30 side elevation, respectively, of our improved shore;

Fig. 3 and 4 are horizontal cross sections in planes A A and B B, respectively, of Fig. 2.

35 Referring now to the said drawings, *a* designates the relatively fixed or stationary member of the shore and *b* the sliding member which by its adjustable sliding attachment to the fixed member *a* may be extended 40 to overlap the same and thus vary and extend the length of the shore as may be desired to any distance permitted by the structural limits.

In the present illustration the member *a* is shown as a tube section of iron or steel and the sliding member *b* as a wooden beam longitudinally recessed at one side to approximately half the diameter of the member *a* which is nested in the trough thus formed.

50 At or near its upper end the tubular member *a* carries a guide yoke *d* fixed thereto and extending completely around the member *b*. At the lower end of the member *b* is attached at each side what may be termed 55 an adjustable shoe *c* consisting of a strong iron or steel plate having an aperture

slightly exceeding the outer diameter of the tubular section *a* which is embraced within said aperture and when in normal position at a right angle with it, slides freely. The 60 plate *c* is carried just below the bottom of the member *b* and is provided with side plate *c*' extending upward at both sides of the member *b* to which it is secured by a pivoted stud *g* extending through both side 65 plates and the intervening member *b*. The shoe thus held has a pivotal support upon the stub *g* with sufficient clearance to allow the plate *c* to "cant" over in relation to the tubular member *a*, as indicated in Fig. 2 of 70 the drawing. Downward pressure upon the member *b* causes the lower edge of the aperture to "bite" into the surface of the tubular member *a* principally at the side indicated at *x*, and also in a lesser degree at the 75 opposite side and edge, and the relation of the parts is such that the greater the pressure the more secure the holding.

In order to hold the plate *c* in locked relations with the tubular member *b* against 80 any tendency to displacement, we attach a set screw *f* by means of a cleat *e* to the outer end of the plate *c*, as shown in Fig. 2, so that the screw bears against the outer side of the member *a* holding the plate *c* in its canted 85 position shown in the figure.

In order to hold the plate in its right angled relation with the member *a* when it is desired to readjust its longitudinal relation to the member *b*, a small piece or "spacer" *h* 90 is employed attached to the bottom of member to contact with the upper face of the plate *c*. When thus used and adjusted, the set screw *f* may be again used to maintain this relation.

95 The head and foot of the device are provided with suitable blocks enlarging the area of contact in parallel planes. These are indicated at *j* and *k* of the drawing but require no further description.

100 In operation the device in its telescoped position of parts is placed where desired (upon a horizontal foundation as nearly as may be) under the object to be supported and the sliding member is raised to the required height and the locking member *c* made to engage the tubular or stationary member. The weight of or pressure against the supported object will keep the parts in 105 locked position. To insure this against accidental displacement, the set screw *f* is tightened.

These operations are reversed by loosening the set screw and setting free the locking member *c* by tapping downward at its outer end, causing the sliding member *b* to drop.

While we have here shown its preferred form as required, in which the sliding member is in a partially telescoped relation with the stationary member, yet our invention 10 may be carried out with tubular members one fully telescoped within the other.

We claim as our invention and desire to secure by Letters Patent of the United States:

15 1. In a shoring device the combination of a relatively stationary element, a member telescopically adjustable thereon, and an integral metallic plate pivoted to one of said members and extending across horizontally 20 and embracing the other member in a perforation of the plate corresponding with the contour of the embraced member and in a sliding fit such that upon canting said plate, the curbs or edges of the perforation are 25 clamped to the embraced element at the contact side and the outer side simultaneously.

2. In a shoring device of the character indicated, a tubular base member; an adjustable extension member partially surrounding said base member in telescopic relations; and a perforated plate pivotally secured at its rear end to the adjustable member and embracing the tubular member in its perforation in such canting relation as to 30 permit free movement of the adjustable member upward but engaging automatically by gravity to prevent intermovement in the other direction by canting action seating the upper and lower edges of the perforation at 35 opposite sides of the base member.

3. An extensible shoring device of the character indicated embodying in combina-

tion a tubular member partially telescoped in and guided upon one face of an inclosing member, and a canting lock or "shoe" 45 having a flat plate below the inclosing member embracing the inclosed member, and provided with side extensions extending upward at opposite sides of the inclosing member to a pivotal connection therewith 50 from side to side.

4. In an extensible shore of the character indicated, in combination with a base member and an extension member relatively movable thereon, a self-operating canting 55 lock pivotally secured to the extension member and embracing the base member, and a retaining screw upon said lock and operating upon the base member to increase the canting angle of the lock to maintain 60 its engagement against accidental displacement.

5. In an extensible shore of the character indicated, in combination with two members relatively extensible one upon the 65 other, a self operating canting lock pivotally secured to one and embracing the other member, and a set screw upon said lock operating to hold the canting lock in engaging position as desired and a "spacer" 70 attached to the bottom of the inclosing member to hold the canting lock out of engagement and permit the free sliding intermovement of the extension member when desired.

In testimony whereof we have hereunto set our hands in presence of two subscribing witnesses.

GEORGE W. MEYER.
CHARLES A. ROOS.
